(57) CLAIM

The ornamental design for a dual scent air freshener with manual combiner, as shown and described herein.

DESCRIPTION

FIG. 1 is an elevated, perspective view of the dual scent air freshener with manual combiner in accordance with my invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in FIGS. 1-7 are for illustrative purposes only and form no part of the claimed design.

1 Claim, 2 Drawing Sheets

FIG. 1FIG. 2*FIG. 3

FIG. 4FIG. 5*FIG. 6*FIG. 7
